UNITED STATES PATENT OFFICE.

WILLIAM O. GOTTWALS, OF WASHINGTON, DISTRICT OF COLUMBIA.

DRAWER-GUIDE.

1,159,490.

Specification of Letters Patent.

Patented Nov. 9, 1915.

Application filed December 4, 1911. Serial No. 663,808.

To all whom it may concern:

Be it known that I, WILLIAM O. GOTTWALS, a citizen of the United States, residing at Washington, in the District of Columbia, have invented certain new and useful Improvements in Drawer-Guides, of which the following is a specification.

The invention relates to that class of drawer guides commonly known as side extension slides, and has for its objects to insure the easy running of the drawer in pulling and pushing it out and in, at the same time attaining simplicity and economy in construction.

In order to make the invention more clearly understood I have shown in the accompanying drawings means for carrying it into practical effect, without limiting my improvements, in their useful applications, to the particular constructions which, for the purpose of illustration, I have delineated.

In the said drawings Figure 1 is a vertical longitudinal section of a vertical filing drawer comprising a drawer guide embodying the invention, on line I—I, Fig. 2. Fig. 2 is a vertical cross-section of the same, to which are added the follower and its rod, on line II—II of Fig. 1. Fig. 3 is a horizontal section of the same on line III—III of Fig. 1, or Fig. 2, the drawer being omitted. Fig. 4 is a sectional view on the same plane as Fig. 2, but on a larger scale, showing a portion of the slide and its supporting roller. Fig. 5 is a side view of the parts shown in Fig. 4. Fig. 6 is a detailed cross-section showing the connection between the slide and the casing. Fig. 7 is a side view partly in section of the front end of the slide, a portion of the drawer and the devices by which the drawer is supported on the slide. Fig. 8 is a transverse section of the same, on line x—x, Fig. 7. Fig. 9 is a detailed cross-section of portions of the slide and drawer, showing a modification, on line y—y, Fig. 10. Fig. 10 is a side view of the same partly in section.

Referring to the drawings, 1 is a case, frame or support in which the drawer 2 is slideable, the latter being mounted upon an extension slide 3 mounted in the case. The invention is illustrated in what is known as a vertical file, for which it is well adapted, and the follower 4 and its supporting rod 5 arranged for holding files and documents

upright in the drawer 2 are shown in Fig. 2; but these parts are omitted in the other figures in order that the elements more particularly pertaining to the invention may be more clearly seen.

6 is a shelf of skeleton form fixed in the case, which latter may entirely inclose the drawer excepting at the front or may be of skeleton form, both constructions being of a known character. On this shelf is mounted 65 the slide 3, which consists of vertical side pieces 7 at the sides of the drawer, a vertical cross-connecting back piece 8 and a front cross piece 9 (preferably of metal) which unites the front ends of the sides 7. On the under side of the median portion of the slide (that is to say about half way between the front and rear ends of the same) are attached metal runners 10 having depending flanges 11, which runners bear on the ends 75 of a transverse roller 12, the flanges 11 entering grooves 13 near the ends of the roller to hold it from endwise movement. Otherwise the roller is loose and serves as a running support for the slide 3; the forward and 80 backward movement of the slide being twice the length of the bodily movement of the roller. The backward movement of the slide is arrested by any suitable stop, such as a block 14 secured on the rear end of the shelf 85 6, and it is stopped in its forward movement at the proper point by the engagement of the roller 12 between depending transverse flanges 15 on the rear ends of the runners 10 and suitable fixtures on the front 90 end of the shelf 6. At one side of the slide such a fixture is supplied by an angle iron 16 which is screwed to the shelf, extends up along the face of one of the sides 7 and has a flange 17 which enters a groove 18 in 95 such side. At the other side of the shelf there is fixed a pin or screw 19 which limits the advance of the roller at that side. When the slide is arrested, therefore, the flanges 15 are in contact with the rear of the roller 100 and the front side of the latter is in contact with the angle iron 16 and pin 19. This engagement of the roller between the two sets of stops re-aligns it if it should not be exactly transverse to the slide and keeps it 105 running properly between the shelf and slide. The rearward movement of the roller may be limited by stops 31 on the shelf 6. The flange 17 and groove 18 hold the slide down in proper position and prevent its 110

- front end being lifted when the drawer is removed. The engagement of the cross piece 9 with the angle iron 16 serves as a stop to the rearward movement of the slide, if they are properly related, and the block 14 may be dispensed with. The back end of the slide 3 is prevented from tilting upward, when the slide is extended by a rail 20 fixed to the inner side of the case, beneath which to the inner side of the case, beneath which 5 engages the back piece 8 of the slide.
- 10 On each side piece 7 of the slide, at its front end, is fixed a cage 21 having a base plate 22 and inwardly inclined side flanges 23, between which latter runs a ball 24. The 15 ball cannot escape through the space between the flanges 23 but projects slightly above them. The base plate is affixed by screws having projecting heads 25 which limit the run of the ball in either direction. On the 20 balls 24 rest the flanges 26 of metal plates 27 attached to each side of the drawer, and on these last mentioned devices the drawer may run forward after the slide is arrested. This last portion of the travel of the drawer 25 is in length twice the bodily movement of the balls 24, and the latter support the drawer from a point in advance of the median line of the drawer to a point in rear of such median line, thus approximately 30 balancing the drawer on the slide. The flanges 26 require to be only as long as the distance between said points. By this balanced arrangement a single ball in each 35 cage gives a perfectly free and easy movement to the drawer. The drawer is or may be stopped in its rearward movement by a stop on the case or by the back piece 8 of the slide. The forward movement of the drawer on the slide is arrested by a stop 28 on the 40 drawer engaging a shoulder 29 on the slide. The stop 28 also engages beneath the rail 20 to prevent the rear end of the drawer from tilting upward.
- 45 If the drawer should be pulled out leaving the slide in place within the case the rolling support of the drawer and slide combined would be the roller 12, and the parts would obviously be out of balance and the subsequent drawing out of the slide would be difficult. It is therefore provided that the slide 50 shall accompany the drawer in the first half of the outward movement of the latter so that the slide and drawer combined shall be properly balanced on the roller 12. To this 55 end I effect a temporary connection between the drawer and slide when they start from their initial position within the case, sufficient to enable the drawer to pull the slide out until the latter is positively arrested.
- 60 This is accomplished by a friction device, preferably a spring or springs 30 attached to the slide with which engages the side of the drawer. After the slide has thus been drawn out to its limit by the drawer any 65 further pull on the drawer disengages it from

the spring and it completes the last half of its outward movement properly balanced on the balls 24.

In combination with the friction device 70 30, my invention includes any form of anti-friction rolling devices which may be substituted for the roller 12 and balls 24.

The slide may be held down at its rear end and guided in the case by flanges 32 secured to the sides of the case and entering 75 grooves 33 in the sides of the slide pieces 7 (Figs. 9 and 10). Also the drawer may be held down upon the slide by lugs 34 working under flanges 35 secured on the tops of said pieces 7. In such construction openings are 80 left at 36 for the lugs 34 to pass in removing and replacing the drawer from and on the slide. Just in front of these openings are shoulders 37 formed on the slide to be encountered by the lugs 34 to arrest the forward movement of the drawer on the slide. In this modification the friction device 85 consists of a spring or springs 38 attached to the slide beneath the flanges 35 and adapted to press on the lugs 34 and cause the slide 90 to be pulled out with the drawer, in the manner fully described in connection with the springs 30.

When the parts are in position shown in dotted lines in Fig. 1 the drawer may be detached from the slide and removed by tilting up the front end of the drawer until the stop 28 on the drawer is disengaged from the shoulder 29 on the slide, whereupon the stop 28 will pass through the space between the 100 shoulder 29 and the front lower corner of the rail 20.

In the construction shown in Figs. 9 and 10 the drawer is removed from the slide by 105 tilting up its front end until the lugs 34 are disengaged from the shoulders 37, whereupon the lugs will pass through the openings 36.

What I claim is:—

1. In a drawer guide, the combination of 110 the casing, an extension slide mounted therein and arranged to be drawn out and to carry a drawer when the latter is outside of the casing, a drawer mounted on the extension slide and adapted to move outward with the slide to a point partly without the casing and thence to move outwardly on and relative to the slide, and adapted to move inwardly on and relative to the slide to a point partly within the casing and thence to move inwardly with the slide to a point within the casing, an anti-friction device mounted and rolling bodily forward and backward beneath the median part of the extension slide and on the forward part of the casing 115 to substantially balance both the slide and drawer while they are moving in unison, an anti-friction device mounted and rolling bodily forward and backward beneath the median part of the drawer and on the for- 120
12. This is accomplished by a friction device, preferably a spring or springs 30 attached to the slide with which engages the side of the drawer. After the slide has thus been drawn out to its limit by the drawer any 125 further pull on the drawer disengages it from the spring and it completes the last half of its outward movement properly balanced on the balls 24.
13. In combination with the friction device 30, my invention includes any form of anti-friction rolling devices which may be substituted for the roller 12 and balls 24.

ward part of the extension slide to substantially balance the drawer individually while it is moving on and relative to the extension slide, and means for temporarily connecting the drawer with the extension slide during the first part of their outward movement to cause them to move in unison both balanced on the first mentioned anti-friction device, substantially as and for the purposes described.

2. In a drawer guide, the combination of a casing or frame, a slide within the same, flanges on the slide, a friction device carried on the slide beneath one of said flanges, an anti-friction rolling device interposed beneath the median portion of the slide, a

drawer on the slide having lugs adapted to slide beneath said flanges and engageable by the said friction device, and an anti-friction rolling device interposed between the median portion of the drawer and the slide, whereby the slide is caused to be pulled out with the drawer and both balanced on the first mentioned rolling device and the drawer individually balanced on the second rolling device, substantially as set forth.

In testimony whereof I affix my signature in presence of two witnesses.

WILLIAM O. GOTTWALS.
